105,158

DESIGN FOR A FISH LURE

Harry Richards Weaver, Wilkes-Barre, Pa.

Application May 4, 1937, Serial No. 69,147

Term of patent 7 years

To all whom it may concern:

Be it known that I, Harry Richards Weaver, a citizen of the United States, residing at Wilkes-Barre, in the county of Luzerne and State of Pennsylvania, have invented a new, original, and ornamental Design for a Fish Lure, of which the following is a specification, reference being had to the accompanying drawing, forming part thereof,

Figure 1 is a side elevation of a fish lure showing my new design.

Figure 2 is a plan view thereof.

I claim:—

The ornamental design for a fish lure, as shown,

HARRY RICHARDS WEAVER.
